US00D990646S

(12) **United States Design Patent** (10) Patent No.: **US D990,646 S**
(45) Date of Patent: ** *Jun. 27, 2023

(54) **AIR PURIFIER**(71) Applicant: **Instant Brands Holdings Inc.**,
Downers Grove, IL (US)(72) Inventors: **Tania Aldous**, Niles, IL (US); **Tyler Brunner**, Durand, WI (US)(73) Assignee: **Instant Brands Holdings Inc.**,
Downers Grove, IL (US)

(*) Notice: This patent is subject to a terminal disclaimer.

(**) Term: **15 Years**(21) Appl. No.: **29/776,424**(22) Filed: **Mar. 30, 2021**(51) LOC (14) Cl. **23-04**

(57) **CLAIM**

The ornamental design for an air purifier, as shown and described.

DESCRIPTION

FIG. 1 is a perspective view of an air purifier showing the new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines depict portions of the air purifier that form no part of the claimed design.

1 Claim, 6 Drawing Sheets
